UNITED STATES PATENT OFFICE

171,561

WHEEL BALANCING WEIGHT

William P. Smissen, Kokomo, Ind.

Application December 3, 1952, Serial No. 22,523

Term of patent 7 years

(Cl. D14—30)

To all whom it may concern:

Be it known that I, William P. Smissen, a citizen of the United States, residing at Kokomo, in the county of Howard and State of Indiana, have invented a new, original, and ornamental Design for Wheel Balancing Weight, of which the following is a specification, reference being had to the accompanying drawing, forming part thereof.

In the drawing:

Figure 1 is a plan view of a wheel balancing weight, showing my new design;

Figure 2 is a side elevation of the same; and Figure 3 is a transverse cross-section of the

same shown in end elevation on an enlarged scale.

I claim:

The ornamental design for a wheel balancing weight, as shown.

WILLIAM P. SMISSEN.
